UNITED STATES PATENT OFFICE.

WILLIAM G. CROCKER, OF LISBON, NORTH DAKOTA.

ADDRESSING ATTACHMENT FOR TYPEWRITERS.

1,388,099.

Specification of Letters Patent. Patented Aug. 16, 1921.

Application filed January 25, 1921. Serial No. 439,808.

To all whom it may concern:

Be it known that I, WILLIAM G. CROCKER, a citizen of the United States, residing at Lisbon, in the county of Ransom and State 5 of North Dakota, have invented certain new and useful Improvements in Addressing Attachments for Typewriters, of which the following is a specification.

My invention relates to attachments for 10 guiding and holding envelops of various sizes, postals, cards, stencils, index cards, and the like, as they are fed to the platen of a typewriter and while being written upon. These articles are usually small, and 15 under ordinary conditions carry but a few short lines of printed matter. They are not easily inserted into the typewriter, alined, and held in place during the printing operations, with typewriting machines as ordinary 20 equipment for office work. It is therefore the object of my invention to produce a simply constructed article, of few parts, and that may be cheaply manufactured, which can be easily and quickly applied to a typewriter 25 when cards are to be printed, and as easily removed therefrom when the typewriter is to be put to its ordinary use of writing upon larger and more flexible sheets. By the use of my invention a card may be 30 introduced into the typewriter in front of the platen, instead of from the back thereof as is the ordinary practice in using typewriting machines, the bottom or following edge of the card being placed between the 35 platen and the attachment and carried downwardly and backwardly by a short reverse movement of the platen in order to bring the card to the desired position to receive the first line of printed matter that is to appear 40 thereon. Those features which characterize my invention will be pointed out in the following specification and are illustrated in the accompanying drawings. Throughout 45 this specification I use the word "card" in an inclusive sense, rather than specifically, to designate the piece written upon, whether that be an envelop, large or small, an index card, a piece of stiff paper, a stencil that is to be cut by the type of the typewriter, or other 50 like article, of whatever size, to be operated upon by the types of the typewriter, such article usually, although not necessarily, being of small size and stiff, as compared with the sheets used in the ordinary work of the

typewriting machine to which my attachment may be applied. 55

My invention is adapted to be used in connection with front-strike typewriters of the commercial styles now in use, it requiring only slight modifications in form and size 60 to adapt it to the particular machine with which it is to be used. A single form of the article may be adapted for use upon any one of two or more typewriters when the parts of such machines with which the attachment 65 is directly associated are similar in size and relative location. In the accompanying drawings I have illustrated my invention as adapted for use upon Underwood and Remington typewriting machines. 70

In such drawings—

Figure 1 is a perspective view of the attachment, detached.

Fig. 2 is a perspective view of my invention applied to an Underwood typewriter. 75

Fig. 3 is a transverse sectional view of the parts illustrated in Fig. 2.

Fig. 4 is a view of the invention applied to a Remington typewriter.

Fig. 5 is a broken perspective view illustrating one manner of securing the attachment to a typewriter carriage frame. 80

Fig. 6 is a detached view of the plate 30 employed in a machine like that shown in Fig. 2. 85

Referring to the drawings, 2, 2 indicate the end frame pieces of the typewriter carriage, in which is mounted the platen 3. At the ends of the shaft of the platen are the usual finger disks 4 by which the platen may 90 be turned. In rear of the platen is the paper shelf 5, and below it the bottom paper apron 18, and the front and rear paper feed rolls 6 and 7. These rolls may be moved away from the platen to release the paper by means of 95 the paper release lever or key 8. The parts thus far described are of well known construction and are found in modified form and arrangement in most, if not all, of the typewriting machines now in common use. 100 The same reference characters are used in Figs. 2, 3 and 4, to designate the parts that are similar in function, although they differ in form and location.

The attachment constituting my invention 105 comprises a plate 9, formed preferably of thin resilient material, such as sheet metal. It is preferably of a length a little less than

the distance between the inner edges of the opposite end frame pieces 2 of the typewriter carriage, so as to be readily supported between these. Through the central portion 5 of the plate 9 is an opening 10, formed by cutting away the material thereof, of a size to expose as much of the card A as it is desired should be written upon. The type, carried by the type bar 11, operates upon 10 the card through this opening, from the front. The lower portion, 12, of the plate is curved slightly so that when the attachment is in use it will lie close to and be approximately concentric with the face of the platen. This part of the plate is preferably 15 slotted, at 28, to receive the front paper feed rolls 6, which are moved away from the platen by means of the release lever 8 to permit this, when the attachment is applied to 20 the typewriter. The rolls which are spring-pressed toward the platen, operate through the slots in plate 9 to hold the said lower curved edge of the plate in proper position close to the face of the platen, and to press 25 the card securely against the platen, thus assisting in feeding the same and in spacing.

16, 16 designate rollers carried by the plate at either side of the opening 10, and with their axis of rotation approximately coinciding with the printing line when the attachment is properly applied to the typewriter for use. They operate to hold the card firmly against the platen in position to be 30 printed upon and assist in feeding and spacing. They are mounted upon shafts 18 supported in flanges 19 turned up from the material forming the plate 9 and operate in openings 17 formed through the plate. The attachment is provided with another roller 35 20 adapted to bear upon the card above the printing line and to assist in holding it against the platen, so that the key may strike the card solidly. This roller is carried by a swinging arm 21 pivotally supported 40 by the cross piece 22 of the plate 9 located above the opening 10. In some typewriting machines the roller 20 and its carrying arm might interfere with the type, and when this is the case it can be swung to one 45 50 side as represented in Fig. 4.

At the ends of the plate 9 are pivoted catches 23 adapted to be caused to engage with the end frame pieces 2 of the carriage in typewriters constructed like the Underwood typewriter machine, as indicated in 55 Fig. 5. The outer edges of the catches are notched as at 24 to facilitate secure engagement between them and the typewriter frame when the catches are swung outwardly into 60 holding positions. These catches serve to hold the attachment securely in working position and are easily operated both to secure the holder when it is applied to the machine and to release it when it is desired to remove 65 the attachment. The catches 23 are typical

of holding means adapted to be brought into engagement with the frame of the typewriter for holding the attachment in place and may be widely varied to suit the particular typewriting machine for which the holding attachment may be made.

25, 25 represent tangs struck up from the material of the plate 9 and located between the central opening 10 therein and its ends. They are in position to engage with the 75 arms 26 carrying the paper margin rolls of a Remington typewriter, as represented in Fig. 4. They pass through the openings in which lie the paper margin rolls 27, directly below such rolls, and engage with the edges 80 of the arms bounding said openings and thus serve to hold the attachment in place. The arms 26 are adjustable longitudinally relative to the platen, and are shifted into proper positions to be engaged by the tangs 85 25 when the attachment is to be applied to the typewriter. These tangs are not used when the card holding plate is applied to an Underwood typewriting machine, the swinging catches 23 being used instead; while on 90 the other hand, the catches are not used when the attachment is applied to a Remington typewriting machine, the tangs then serving as the holding means. It might be with certain types of machines that both holding 95 means could be used together. The article shown in Fig. 1, as has been explained, is adapted for use upon two well-known and extensively used typewriting machines.

In applying the attachment to an Underwood typewriter, the arms 26 carrying the paper margin rolls are thrown out of the way as indicated in Fig. 2. The release lever 8 is then adjusted to move the paper feed rolls 6 and 7 away from the platen. The 100 card-holding plate 9, with its curved edge 10 downward and its concave face toward the platen, is then inserted between the end frame pieces of the typewriter carriage in front of the platen and moved downwardly, 105 its lower curved edge being held in contact with the platen. While the attachment is being put into position the front feed rolls 7 are preferably moved away from the platen, 110 by the paper release lever 8 until the attachment is in place when the said rollers will lie in the slots 28. The rollers 7, bearing against the card, hold it in proper position close to the face of the platen and near the front edge of the bottom paper apron 13. When the 115 card-holding plate has been adjusted to proper working position the catches 23 are moved outwardly to engage with the frame pieces of the carriage and hold or lock the plate in position. The card, A, to be written upon is inserted, from above, between the platen and the rubber rollers in the holding plate 9. A slight reverse movement of the platen will then carry the card backwardly 120 to the desired position to receive the first 125 130

line of writing. The address or other matter to be written upon the card is now printed in the ordinary way, and spacing is performed as ordinarily.

- 5 When the attachment is to be applied to a Remington typewriter the arms 26 carrying the paper margin rolls are adjusted to positions to be engaged by the tangs 25. The holder is then inserted in the same way as has just been described in
 10 connection with the Underwood typewriter except that the arms 26 have to be sprung forwardly sufficiently to permit the tangs to pass behind them until they come opposite the slits below the paper margin rolls, when
 15 the tangs will enter such slits and hold the attachment in position.

The attachment constituting my invention may be applied to the typewriting machine for which it is fitted in a few seconds time.

- 20 Its application does not require the use of a skilled operator or the use of any tools. When its use is no longer required it may be easily and quickly removed, whereupon the typewriter is in condition for ordinary uses, 25 since the application of the attachment does not require the removal of any of the parts of a typewriter, nor the addition of any parts, except in some models of the Underwood typewriter which require a small plate
 30 30, Figs. 2 and 6, at the left end of the carriage to be engaged by the catch 23 that swings outwardly to the left. This plate is attached by simply removing a set screw ordinarily found in typewriters of this type, 35 and after the plate 30 has been put in position replacing the screw in the hole in the plate. The plate then remains on the machine and does not interfere with the regular work. Its edge is preferably notched as
 40 indicated at 30, Fig. 6, to coöperate with the notched edge of the catch 23.

Having described my invention what I claim and desire to secure by Letters Patent is:

- 45 1. A card-holding attachment adapted to be applied to a front-strike typewriting machine in front of the platen thereof, comprising a plate having an opening exposing the card to be written upon, through
 50 which the type may operate, the lower end of the plate being curved to conform to the curvature of the platen and lie close to the face thereof when the attachment is in use,

and the upper portion of the plate being fitted with rollers to direct the card toward the 55 said lower edge and carrying means by which the plate is united with the paper carriage and held in place relative to the platen.

2. A card-holding attachment adapted to 60 be applied to a front-strike typewriting machine in front of the platen thereof, comprising a plate having a centrally located opening through which the card to be written upon is exposed, the lower portion of the 65 plate extending below the said opening and operating to hold the card close to the platen of the typewriter, and means located between the said central opening and the ends of the plate for connecting the attachment with the 70 carriage of the typewriter and holding it in position for use.

3. A card-holding attachment adapted to 75 be applied to a front-strike typewriting machine, comprising a plate having a centrally located opening through which the card to be written upon is exposed, the lower portion of the plate extending below and across the said opening and operating a plurality of sets of means for connecting 80 the attachment with the carriage of a typewriter, one element of each set being located between the central opening of the plate and each end thereof, and one set of means being adapted for use in connecting the attachment to the carriage of a typewriter of one make, and another set to be used in connecting the attachment to the carriage of a typewriter of another make.

4. The combination with the cylindrical 90 platen of a typewriter, the under paper feeding means associated therewith, and means for moving away from the cylinder the said paper feeding means, of an attachment for holding cards against the platen while being printed upon consisting of a separable plate with an opening through it through which the types act upon the card and provided with a curved lower edge adapted to be inserted between the platen and the paper 95 feeding means and to be held close to the platen, and easily adjustable means for connecting the platen with a typewriting carriage to hold the former in place.

WILLIAM G. CROCKER.
